UNITED STATES PATENT OFFICE.

GEORGE S. HENSEL, OF PHILADELPHIA, PENNSYLVANIA.

DESIGN FOR A SKIRT-PROTECTOR.

SPECIFICATION forming part of Design No. 30,300, dated February 28, 1899.

Application filed January 30, 1899. Serial No. 703,946. Term of patent 14 years.

To all whom it may concern:

Be it known that I, GEORGE S. HENSEL, a citizen of the United States, residing in the city and county of Philadelphia, State of Pennsylvania, have invented and produced a new and useful Design for a Skirt-Protector, of which the following is a specification, reference being had to the accompanying drawings, forming part thereof.

- 10 The leading feature of my design for a skirt-protector is a head and a brush pendent from the bottom edge thereof, said head having a longitudinal line of transverse ridges along its top edge, longitudinally-extending 15 ridges just below said transverse ridges, a longitudinal line of transverse ridges below said longitudinal ridges, and a second line of longitudinally-extending ridges between the second line of transverse ridges and the top 20 edge of the brush.

Figure 1 represents a face view of a piece of skirt-protector embodying my design. Fig. 2 represents a section thereof.

In the drawings, A designates a piece of skirt-protector, the same consisting of the ²⁵ head B, the brush C, pendent from the lower edge thereof, and the longitudinal lines of transverse ridges D and E and lines of longitudinal ridges F and G on the sides of said head.

Having thus described my invention, what I claim as new, and desire to secure by Letters Patent, is—

The design for a skirt-protector substantially as shown and described.

GEORGE S. HENSEL.
